THEODORE C. VAN TRABERT, OF BRONX, NEW YORK

RADIORECEIVER

Continuation of application Serial No. 233,748, filed November 17, 1927. This application filed January 23, 1928. Serial No. 248,792.

My invention relates to radio receivers and particularly to the circuit connections and apparatus of an improved receiver that is particularly adapted for broadcast reception; this application being a continuation of my prior application, Ser. No. 233,748, filed November 17, 1927.

One object of the invention is to provide an improved receiver which employs ordinary amplifier tubes of the filamentary-cathode type but which does not require any batteries, acid rectifiers or the like.

Another object of my invention is to simplify the construction of the receiver without sacrificing volume or tone quality and to provide apparatus in which extraneous noises and disturbances are reduced to a minimum.

Another object of my invention is to provide an arrangement of circuits and apparatus in which amplifier tubes of the filamentary-cathode type may be employed for amplifying signals or voice currents wherein the cathodes are energized directly from an alternating current source without introducing any alternating current "hum" such as is ordinarily obtained in an amplifier of this character.

A still further object of my invention is to provide an improved B battery-eliminator of simple construction and which provides improved results in connection with the amplifier above referred to.

The radio receiver embodying my invention may comprise filamentary-cathode tubes, such as those commonly designated as Type 201-A, which are energized directly from an alternating current source, such as a step-down transformer. These tubes are the cheapest and most highly developed and practical type of amplifier for the purpose available at the present time, and heretofore their use with alternating current cathode current has been considered undesirable because of the alternating current "hum" obtained in the output circuit. It is an important feature of my invention that by an improved circuit arrangement, not only is the alternating current "hum" completely eliminated without sacrificing volume and tone

quality, but it is found that the receiver is much less subject to extraneous disturbances caused by static conditions or the like which in the ordinary set render the character of the music or sound received displeasing or indistinct under all except ideal conditions. 55

Other objects and advantages of my invention will become apparent from consideration of the accompanying drawings, the 60 single figure of which is a diagrammatic view of a radio receiving set embodying the invention.

Referring to the drawings, the receiving set embodies an antenna circuit 1, a radio 65 frequency amplifier 2, including the amplifier tube 3, a detector 4 and an audio frequency amplifier 5 including amplifier tubes 6 and 7.

The circuits of the set may be modified in various ways except in respect to the portions described in detail hereinafter but for the purpose of disclosing the invention, a circuit including a tightly coupled tuned antenna circuit is shown together with one stage of radio frequency amplification and a crystal detector. It will be apparent from the following description of the invention that a loosely coupled antenna circuit may be employed or more than one stage of radio frequency amplification, either tuned or un-tuned, or an electro-ionic tube detector in place of the crystal detector 4. 70 75 80

The specific modification of the radio receiver which is shown in the drawing comprises two tuning controls which are variable condensers 8 and 9 in the antenna circuit and in the radio frequency amplifier, respectively. The only other controls that are necessary are a switch for turning off the supply of power from the 110 volt alternating current circuit 10 to the set and a volume control, such as the variable resistance 11 bridged across the loud-speaker jack L. S. or connected in any well known manner to control the output current from the set. 85 90 95

The antenna circuit includes the inductance coil 12 which forms with the condenser 8 a circuit which is resonant to the frequency being received, and fixed condensers 13 and 14, respectively. The condensers 13 and 14 100

are connected in series relation in the antenna circuit and one terminal of the condenser 14 is connected to the usual ground connection.

5 The condenser 13 is of about $\frac{1}{2}$ to 4 m. f. capacity, preferably 2 to 4 m. f., and is an essential element of the circuit as will be explained hereinafter. The condenser 14 is of approximately $\frac{1}{4}$ m. f. capacity and is only 10 for the purpose of protection in case of an accidental short-circuit between the 110 volt supply circuit or other high-voltage circuit and the circuits of the radio receiver. This condenser may be omitted if desired without 15 affecting the operation of the set.

The antenna circuit is connected through a resistor 15 to the control electrode of the radio frequency amplifier tube 3. The resistance of the resistor 15 is appreciable and may 20 be relatively high for example a ballast resistance such as an "amperite" and having a resistance of about 25 ohms at $\frac{1}{4}$ of an ampere may be used or a grid leak and parallel condenser may be used. The plate electrode of the amplifier tube 3 is connected through a radio frequency transformer 16 to the crystal detector 4, the secondary circuit of the transformer being tuned by the condenser 9 and containing a resistor 17 25 which may be another "amperite" of the same characteristics as that used in the input circuit of the amplifier tube 3.

The crystal detector circuit is connected through audio-frequency transformers 20 35 and 21 and the audio-frequency amplifier tubes 6 and 7 in substantially the usual manner to the output circuit which is shown as connected to the loud-speaker jack L. S.

40 The dimensions and arrangement of the turning elements in the receiver depend upon the frequency of the current for which the set is designed to respond and may be variously modified to meet the conditions encountered in actual practice. For a receiver designed to cover the present range of wavelengths from 200 to 600 meters, the condensers 8 and 9 may be of .0005 m. f. capacity, and the inductance 12 comprise about 20 to 50 turns of #24 enamelled wire wound on 45 a $3\frac{1}{8}$ inch bakelite tube, depending upon the length of the antenna and whether a capacity antenna or loop antenna is used. The primary of the radio frequency transformer 16 may be of 32 turns of #24 enamelled wire on 50 a $2\frac{1}{4}$ inch tube, preferably wound in two halves with $\frac{5}{8}$ inch spacing between the coil sections. The secondary winding may be 55 60 turns of the same wire on a $3\frac{1}{8}$ inch tube with the same spacing between the two half-sections.

The amplifier tubes 3, 6 and 7, and also the detector 4 where a vacuum tube detector is employed, are energized from the alternating-current supply source 10 through a step-down 65 transformer 25 of the proper ratio to provide

the desired low voltage for the filament circuits of the tube. In the case of type 201-A tubes, the applied voltage should be 5 volts to insure long life of the tubes.

I have found that the values of filament 70 current employed in the separate tubes is an important factor in eliminating the alternating current "hum" and accordingly a control rheostat 26 is provided in the circuit of the radio frequency amplifier tube 3 and another control rheostat 27 in the circuit of the audio frequency amplifier tubes 6 and 7. Ballast resistance having the proper characteristics may be substituted for these rheostats.

Two potentiometers 28 and 29 are also bridged across the cathodes of the radio and audio frequency amplifier tubes respectively. An inductance or similar impedance having a mid-point tap may be substituted for either 85 of these potentiometers.

Although the control rheostats and the potentiometers are shown as variable, the voltage of the standard lighting circuit is sufficiently constant so that after these elements are initially adjusted to the proper point, no further adjustment is necessary. It is preferable to have the potentiometer 28 of rather high resistance, for example about 1800 ohms. The potentiometer 29 may be of lower resistance, for example 300 ohms.

The supply of current for the plate circuits of the tubes is shown as a B-battery 95 eliminator of the double-wave rectifier type, although ordinary batteries may be employed. 100 This rectifier may be mounted in close proximity to or in the same cabinet with the receiver. Instead of using special rectifier tubes, I have found after considerable experimentation that an exceedingly simple and 105 practical rectifier may be constructed with the particular apparatus hereinafter described and using two Type 201-A amplifier tubes as rectifiers. The rectifier tubes are indicated at 30 in the drawing. The filamentary cathodes of the tubes 30 are energized from a transformer 35 similar to the transformer 25, and the grid and plate electrodes of the tubes are connected together, as indicated.

110 The filter circuit of the rectifier includes two iron core chokes 31 in series with the output circuit of the rectifier, each choke having an inductance of approximately 30 henries. The bridging condensers 32 and 33 connected across the leads of the rectifier are 115 preferably of 4 m. f. and 8 m. f. capacity, respectively. In addition, one of the chokes 31 is shunted by a third condenser 34 of about 2 m. f. capacity.

120 The high potential for the rectifier may be obtained from any high grade step-up transformer which is connected to the supply circuit 10. However, I prefer to use two audio 125 transformers 36 and 37 such as are commonly

employed in the audio frequency amplifiers of radio sets and having a ratio of about 3 to 1. The transformers used for this purpose must be carefully chosen for good insulation and heat-dissipating capacity and should also 5 have tightly clamped laminations so that no mechanical hum is introduced from this source. I have found that these transformers which are relatively inexpensive may be connected for this purpose across a 110 volt 10 supply circuit in the manner indicated without any appreciable temperature rise and with very satisfactory results. The transformers and chokes are preferably shielded 15 from the set in the usual manner and the shield may be grounded to the usual ground connection. This ground connection may be either that shown in connection with the condenser 14 or the ground connection commonly provided for one side of the supply 20 circuit 10.

There are a number of factors which must be carefully considered in constructing a set 25 of this character to eliminate the alternating current "hum" with the use of alternating current filament supply without sacrificing volume and tone quality and I have found that, besides the rheostats and potentiometers 26, 27, 28 and 29 already referred to, the resistors 15 and 17 and the condenser 13 are 30 important factors. In addition, I have provided two other condensers, 40 and 41, each of approximately 2 m. f. capacity, the first being connected to the tuned radio frequency amplifier 35 circuit and the point 44 as indicated, and the second between the plus terminal of the plate current supply and the antenna circuit. The condenser 40 may be connected to the point 45 instead of the point 44, and the 40 size of the condenser 41 may be as large as about 4 m. f.

By a series of tests, I have proven that 45 these elements connected as indicated and of the described characteristics are responsible for the improved results that are obtained. For example, if the condenser 13 be short-circuited in a set that is built according to the diagram shown on the drawing, a pronounced 50 alternating current "hum" is heard which cannot be eliminated by adjusting the filament controls 26, 27, 28 and 29.

From an inspection of the drawing it will be seen that condensers 13 and 41 are connected in series across the plate current supply 55 source, and the grid circuits of all the amplifiers are connected to a point between the condensers. While I am unable to offer a satisfactory theory of operation, I have found by experiment that this particular arrangement of elements is effective in materially 60 reducing the interfering hum to a minimum. I have also found that an ordinary "C" battery of 4½ volts may be substituted for condenser 13 without any apparent 65 change in operation, but in accordance with

one of the objects of my invention, I prefer to use an arrangement containing no batteries.

I am aware that relatively low resistances have been connected in substantially the same relation in a radio frequency amplifier as the resistances 15 and 17 to cut down the 70 tendency of an amplifier to oscillate. I have found, however, that by using resistances of the stated character, the additional advantage is obtained that the set is less responsive to extraneous disturbances, such as commutator noises and static discharges and there is also a decrease in the tendency of the set to produce an alternating current "hum." It 75 seems obvious that the result of the introduction of the resistances 15 and 17 is to substantially cut down the amplification ratio 80 for currents appreciably different from the frequencies for which the circuits 1 and 2 are tuned, but I am unable to advance a theory 85 of operation to explain this result.

The practical advantages of a radio receiver embodying my invention are many although perhaps the most important is the production of a simple and efficient set using 90 tubes provided with filamentary cathodes but requiring no batteries or the like. In many of the so-called electrical or "batteryless" sets being offered at the present time, there is an appreciable alternating current "hum" 95 even though most of these sets embody tubes especially designed for this purpose and costing several times as much as the Type 201-A tube. It should be noted that all of the tubes in the present set are alike even those in the 100 plate current rectifier, although the tube 7 may be a larger tube where the volume of output current is great.

While the absence of alternating current "hum" in a set of this character is an important factor and one which will become more 105 important as those using radio sets become more critical, the present set is also remarkable for its tone quality and freedom from extraneous noises. There appears to be no distortion in the voice currents received and the set is exceedingly quiet even when operated under conditions that are far from ideal.

Apparently the condensers 13, 40 and 41 110 serve to improve the operation of the receiver in relation to its freedom from extraneous noises as well as in the elimination of alternating current "hum."

One of the sets has been operated in a locality where there are several motors connected 120 to the circuit to which the set is connected and in a crowded area surrounded by apartment house buildings containing compressors and elevators. Even under these conditions the noise, which attains considerable volume 125 in an ordinary receiver in this locality, is not only reduced so that it is not objectionable but it is substantially eliminated.

Furthermore, the receiver described is not 130 appreciably affected by "body" capacity and

ordinarily no shielding is provided for the panel or the condensers and inductances.

The described arrangement and organization of the elements of a receiver may be modified as indicated above without departing from the spirit of the invention and I desire to include all such modifications and changes as fall within the scope of the appended claims.

I claim:

1. A radio receiver embodying an antenna circuit, a radio frequency amplifier, a detector and an audio frequency amplifier, said amplifiers comprising an electro-ionic tube having a filamentary cathode, a source of alternating current for energizing the cathodes of said tubes, a potentiometer bridged across said cathodes, a condenser of relatively large capacity in series with the antenna circuit, one terminal of said condenser being connected to ground through a circuit having negligible impedance for radio-frequency currents and a connection between the last-mentioned terminal of said condenser and the intermediate tap on said potentiometer.
2. A radio receiver embodying an antenna circuit, a radio frequency amplifier, a detector and an audio frequency amplifier, said amplifiers comprising tubes provided with cathode and grid and plate electrodes, means for energizing said tubes and a condenser of the order of 2 m. f. capacity in the grid circuits of the amplifier tubes, one terminal of said condenser being connected to ground through a circuit having negligible impedance for radio-frequency currents.
3. A radio receiver embodying an antenna circuit, a radio frequency amplifier, a detector and an audio frequency amplifier, said amplifiers comprising an electro-ionic tube having a filamentary cathode, a source of alternating current for energizing the cathodes of said tubes, and a condenser of approximately two m. f. capacity in series with the antenna circuit, one terminal of said condenser being connected to ground through a circuit having negligible impedance for radio-frequency currents.
4. A radio receiver embodying an antenna circuit, a radio frequency amplifier, a detector and an audio frequency amplifier, said amplifiers comprising an electro-ionic tube having a filamentary cathode, a source of alternating current for energizing the cathodes of said tubes, a condenser of relatively large capacity in the antenna circuit, one terminal of said condenser being connected to ground through a circuit having negligible impedance for radio-frequency currents and a second condenser connected between the last-mentioned terminal of the first-mentioned condenser and the plus terminal of the plate current supply source.
5. A radio receiver embodying an antenna circuit, a radio frequency amplifier, a detec-

tor and an audio frequency amplifier, said amplifiers comprising an electro-ionic tube having a filamentary cathode, a source of alternating current for energizing the cathodes of said tubes, a condenser of relatively large capacity in the antenna circuit, one terminal of said condenser being connected to ground through a circuit having negligible impedance for radio-frequency current, and a condenser connected between the other terminal of the first-mentioned condenser and the plus terminal of the plate current supply source, the grid circuits of said amplifiers being connected to a point between said condensers.

6. An amplifier embodying a parallel-resonant circuit comprising inductance and capacity, an electro-ionic tube having its input electrode connected to one of the terminals of said inductance and a relatively large condenser connected to the other terminal of said inductance and to ground through a circuit having negligible impedance for radio-frequency currents.

7. A radio receiver embodying an antenna circuit, radio and audio frequency amplifiers of the filamentary cathode type provided with control electrodes and a detector, means for energizing the cathodes of said amplifiers with alternating current, balancing circuits between the cathodes and ground potential and a condenser of relatively large capacity connected in the antenna circuit, said condenser being also in the cathode-control electrode circuit of the first radio frequency amplifier and traversed by the entire current flowing therein.

8. An amplifier comprising a thermionic relay having a filamentary cathode, a grid and a plate, a source of alternating current for energizing said cathode, an input circuit connected at one side to the cathode circuit effectively at the electrical mid-point of said cathode and at the other side to said grid, said input circuit including a series condenser of relatively large capacity traversed by the entire current flowing between cathode and grid.

9. An amplifier comprising a thermionic relay having a filamentary cathode, a grid and a plate, input and output circuits for said relay, a source of energizing current in said output circuit having a disturbing component, a path across the terminals of said source including two condensers in series, one side of said input circuit being connected to said path between said condensers, and the other side being connected to the grid of the relay.

10. An amplifier comprising a thermionic relay having filament, grid and plate elements, a source of alternating current for energizing said filament, a potentiometer in shunt to said filament, an output circuit connected between the plate element and the movable contact element of said potentiometer, a source of energizing current for the

output circuit having a disturbing component, two condensers connected in series in a path across said output current source, and an input circuit connected at one side to the 5 grid element and at the other side to a point between said condensers.
